UNITED STATES PATENT OFFICE.

ERNEST A. BARFIELD, OF MACON, GEORGIA.

CARD HOLDER.

Application filed January 15, 1925. Serial No. 2,665.

To all whom it may concern:

Be it known that ERNEST A. BARFIELD, a citizen of the United States, residing at Macon, in the county of Bibb and State of Georgia, has invented certain new and useful Improvements in Card Holders, of which the following is a specification.

This invention relates to display devices and has special reference to card holders for freight cars and the like.

10 The common manner of attaching destination and other cards to a freight car is by tacking them in place on the car door or other convenient position. This ultimately results in much injury to the car.

15 One important object of the invention is to provide a novel general construction of card holder especially adapted for holding such cards as are usually displayed on a freight car and which may be manufactured in a highly economical manner.

20 A second important object of the invention is to provide a device of this description formed of a single length of spring wire bent and arranged in a novel manner.

25 A third important object of the invention is to provide, in a device of this sort formed of wire, certain portions of the wire with means to prevent slipping of the card.

30 With the above and other objects in view as will be hereinafter apparent, the invention consists in general of certain novel details of construction and combinations of parts hereinafter fully described, illustrated 35 in the accompanying drawings and specifically claimed.

In the accompanying drawings like characters of reference indicate like parts in the several views, and:

40 Figure 1 is a front elevation of one form of the invention.

Figure 2 is a section on the line 2—2 of Figure 1.

45 Figure 3 is a view similar to Figure 2 showing the device open.

Figure 4 is a perspective view of a second form of the invention.

Figure 5 is a detail showing a modification of one part of the first form.

50 Figure 6 is a view showing one of the means adopted for keeping the card from slipping.

Figure 7 shows a second form of anti-slipping means.

55 Figure 8 shows a third form of anti-slipping means.

In the form of the invention shown in Figures 1, 2 and 3 it will be seen that the device is made from a single length of wire, spring wire being preferably employed. 60 The ends of the wire are united in some suitable manner, here shown as an ordinary splice 10. From the connection point or splice 10 the wire extends in opposite directions as at 11 and each end is then carried up as at 12 thus making a U-shaped frame or member of which the portions 11 form the base and the portions 12 the legs. At the upper end of each leg the wire is bent to form an eye 13 and then extended downwardly and coiled as at 14 to form torsion springs. The wire extends downwardly from these springs parallel to the legs 12 to form the legs 15 of a second U-shaped member and between the lower ends of these legs 70 the wire extends across to form the base portions 16 of said second member, the center of the wire being bent downwardly in U-shape to form a tongue 17. Between the arms of this tongue is located a one-armed turn button 18 forming a latch and swinging to either engage the tongue or lie free therefrom.

In this form of the device the inner member formed by the parts 11 and 12 at all times rests against the door or base 18 while 85 the outer member may be sprung out, as in Figure 3, and a card C inserted between the two. The outer member is then allowed to spring back and clamp the card, the turnbutton 18 being turned to lock it down. 90

To facilitate lifting the outer member, a loop 20 may be formed on one side of the tongue, this loop constituting a finger grip.

As anti-slipping means to prevent accidental dislodgment of the card the legs of one 95 or both of the members may be provided with corrugations 21 as in Figure 7, serrations 22 as in Figure 6, or needle like projections 23 as in Figures 3 and 8.

As a modification a spring coil 24 may be 100 provided at each corner of the outer or movable member as shown in Figure 5.

A modification of the device employing only one member is shown in Figure 4. This form, like the other, is formed from a single 105 length of spring wire doubled and bent to form an attaching eye 25, the parts on each side extending parallel from the eye in the same direction as at 26 and having right angled bends 27. Coiled torsion springs are 110 formed at the ends of the portions 26 and from these springs the wires are extended

first divergingly as at 28 and then convergingly as at 29, coiled springs 30 being formed at the junctions of the diverging and converging portions. The proximal ends of the 5 converging portions 29 are twisted together to form a coil 31 and one of the extremities of the wire extends from the coil to form a tongue 32 engageable by the turn button 33.

In this form the card is simply held beneath the device against the tag-board on which it is mounted.

There has thus been provided a simple and efficient device of the kind described and for the purpose specified.

15 It is obvious that minor changes may be made in the form and construction of the invention without departing from the material spirit thereof. It is not, therefore, desired to confine the invention to the exact 20 form herein shown and described, but it is desired to include all such as properly come within the scope claimed.

Having thus described the invention, what is claimed as new, is:

25 1. A card holder for freight car doors and the like consisting of a single length of spring wire bent to provide a pair of cooperating U-shaped members having securing eyes at the ends of the legs of the U, one of

said members lying close to and within the 30 other member, spring coils formed on the legs of one member adjacent said eyes whereby the free portion of said member may be sprung away from the other member to permit insertion of a card between said members, card gripping means formed on one of 35 said members, a latch tongue formed on the base of said movable member, and a latch pivoted to pass between the sides of the portion of the wire forming said tongue and 40 engaging the swinging member.

2. A card holder for freight car doors and the like consisting of a single length of spring wire bent to provide a pair of cooperating 45 U-shaped members having securing eyes at the ends of the legs of the U, spring coils formed on the legs of one member adjacent said eyes whereby the free portion of said member may be sprung away from the other member to permit insertion of a card 50 between said members, serrations formed on one of said members, a latch tongue formed on the base of said movable member and a latch pivoted to pass between the sides of the portion of the wire forming said tongue 55 and engaging the swinging member.

In testimony whereof I affix my signature.

ERNEST A. BARFIELD.
